DESIGN FOR A CARPET UNDERLINER

Arthur L. Clements, Chicago, Ill., assignor to American Hair & Felt Company, Chicago, Ill.,
a corporation of Delaware

Application November 23, 1934, Serial No. 54,127

Term of patent 14 years

To all whom it may concern:

Be it known that I, Arthur L. Clements, a citizen of the United States of America and residing at Chicago, in the county of Cook and State of Illinois, have invented a new, original, and ornamental Design for a Carpet Underliner, of which the following is a specification, reference being had to the accompanying drawing, forming a part thereof.

In the drawing,

Fig. 1 is a plan view of the carpet underliner showing a portion of the tread surface embodying my design.

Fig. 2 is a section taken on the broken line 2—2 of Fig. 1.

What I claim is:

The ornamental design for a carpet underliner as shown and described.

ARTHUR L. CLEMENTS.
